UNITED STATES PATENT OFFICE.

NICHOLAS L. BIEHL, OF LOS ANGELES, CALIFORNIA.

GARMENT SUPPORT.

Application filed January 29, 1923. Serial No. 615,570.

To all whom it may concern:

Be it known that I, NICHOLAS L. BIEHL, a citizen of the United States, residing at Los Angeles, in the county of Los Angeles and State of California, have invented a new and useful Garment Support, of which the following is a specification.

This invention relates to a garment support adapted to be worn with a garment such as, for example, a skirt or trousers to support the garment from the waist of the person wearing the same.

An object of the invention is to provide a garment support that can be employed in place of the ordinary loose belt worn with trousers to bind the trousers about the waist of the wearer. Such belts are relatively narrow and the weight of the garment tends to pull the belt down, unless said belt is buckled very tightly, in which case some of the organs of the body are unduly compressed.

An object of this invention is to provide for supporting a garment without unduly compressing any of the organs of the body of the wearer.

Another common fault of the ordinary trouser-supporting belt is that the shirt tends to creep up at the waist and pull out of the trousers, thus presenting an untidy appearance. An object of this invention is to provide a garment support that will overcome this fault.

The ordinary belt worn on the outside of the trousers is held in place on the trousers by loops on the outer face of the trousers. Such loops destroy the neat appearance of the trousers at the waist line and the belt oft times slips around the waist through the loops.

Another object of this invention is to provide a garment support that can be worn on the inside of the trousers and readily attached thereto so that relative movement between the trousers and support cannot take place.

A further object of the invention is to so construct the garment support that it will not wrinkle and tend to fold over at its upper margin, due to the weight of the garment attached thereto.

The accompanying drawings illustrate the invention:

Figure 1 shows in dotted lines a garment support constructed in accordance with the provisions of this invention in place with-

in the waist-fitting portion of a garment, as it would appear when being worn, a fragment of a shirt also being shown.

Fig. 2 is an enlarged elevation looking at the inner face of the band shown in Figure 1.

Fig. 3 is an elevation looking at the outer face of the band.

Fig. 4 is an enlarged detail showing one of the fastener members secured to a fragment of the garment.

Fig. 5 is an enlarged sectional elevation on the line indicated by 5-5, Figure 1.

Fig. 6 is an enlarged sectional detail on the line indicated by 6-6, Figure 3.

Fig. 7 is a longitudinal view of a modification of the means for mounting the fastening means on the garment.

There is provided a band, indicated in general, by the character 11. The band is relatively broad and may, if desired, comprise a plurality of sections. In this particular instance the band 11 comprises end sections 12 and intermediate sections 13 constructed of relatively heavy material, preferably of double thickness. The sections 12 are connected to the sections 13 by strips 14, preferably made of elastic webbing. The sections 13 are connected to one another by a strip 141 of relatively thin material and also by adjusting means comprising tapes 15, 16 and buckles 171, so that the girth of the band may be readily increased or decreased to suit the wearer thereof. Preferably the members 12 decrease in width toward the strips 14. This is also true of the sections 13. Thus the band is relatively broad in front and rear and relatively narrow over the hips, adjacent which the strips 14 are positioned. The member 141 is positioned in the middle of the back of the wearer and the sections 12 fit across the abdomen.

Cooperating snap-fastening members 17, 18 or other fastening devices are secured to the free wider ends of the sections 12 so that said ends may be readily connected for securing the band about the waist.

The band is provided with transversely extending busks 27 made of whalebone, steel, or other suitable material and said busks are sewed in place between the two thicknesses of material constituting the sections 12, 13. This is clearly shown in Figure 6, the stitching being indicated at 19. Preferably the busks are positioned in

pairs, the upper ends of the busks of each pair being spaced but slightly.

Cooperating fastening devices are provided at intervals along the upper margin 5 of the inner face of the waist-fitting portion *a* of the garment, indicated at *b*, and the upper margin of the outer face of the band, to detachably secure the garment to the band. The fastening devices on the garment *b* are 10 indicated at 20 and the fastening devices on the band are indicated at 21. In this particular instance the fastening devices 20, 21 are the well known snap fasteners. The fastening devices 21 are positioned on the 15 band between the adjacent upper ends of the paired busks so that when strain comes upon the fastening members the upper margin of the band will not be pulled downwardly and cause the band to wrinkle. Even a relatively heavy garment may thus be supported 20 without inconveniencing the wearer of the garment support since the band is broad and retains its shape under the strain imposed on it. The fastening members 20 are preferably secured to a tape 221 or tapes 22 that 25 are sewed to the inner face of the waist-fitting portion of the garment, the stitches being indicated at 23 in Figure 5. It has been hereinbefore stated that the sections 12, 13 are preferably formed from a double thickness 30 of fabric. The upper and lower margins of the sections 12 are provided with binding strips 24 extending from end to end of each section. The sections 13 are provided 35 on their upper and lower margins with binding strips 25 which also extend along the margins of the strip 141.

It will be clear from the foregoing that, in practice, either the band may be attached to 40 the trousers, before the trousers are donned, the trousers then slipped on, and the ends of the band connected over the shirt by the fastening members 17, 18; or the band may be placed in position about the waist over 45 the shirt and the ends joined, and then the trousers slipped on and secured to the band by connecting the fastening members 20, 21. The elastic strips 14 permit the band to yield sufficiently not to inconvenience movements 50 of the wearer, and at the same time said elastic strips hold the band close about the body so as to prevent downward slipping of the band and the garment attached thereto. Owing to the narrower portions 14 of the 55 band being adjacent the hips, bending and turning movements of the body can be made without inconvenience and without wrinkling and displacement of any of the band sections.

If the busks were placed singly instead of 60 in pairs, the upper margin of the band adjacent the fasteners 21 would not be held rigid as is the case where the busks are paired as shown, for the fasteners extend through the material of the band and, consequently, the fasteners 21 cannot be attached to the band so as to register exactly with the busks. It will also be clear, by referring to Figure 6, that there are formed 65 channels 26 on opposite faces of the band between each two adjacent busks. Thus the fasteners, which protrude from the opposite faces of the band, are accommodated in the channels 26 and will not tend to press into the wearer's body and prove uncomfortable. 70 75

It is to be noted that the tape 221 constitutes a band when secured to the garment and that said band has the advantage that, when the fasteners 20 are attached thereto, said fasteners are properly spaced for engagement with the fasteners 21. Thus the manufacturer will make one or more of the bands 221 with the fasteners 20 in place thereon properly spaced, and the purchaser need only sew the bands in place in the various garments that are to be supported. Thus the application of the fasteners 20 to the garment is facilitated. 80 85

I claim:

1. The combination with the waist-fitting portion of a garment supported at the waist, of a band provided with transversely extending busks arranged in pairs, the upper end of the busks of each pair being slightly spaced, cooperating fastening devices at intervals along the inner face of the waist-fitting portion and the upper margin of the outer face of the band to detachably secure the band to the garment, the fastening devices on the band being between the adjacent upper ends of the paired busks, and means to releasably connect the ends of the band. 90 95 100

2. A garment support comprising a band provided with transversely extending busks arranged in pairs, the upper ends of the busks of each pair being slightly spaced, snap fastener elements between the adjacent upper ends of the paired busks, a plurality of tapes each provided with snap fastener elements spaced the same as the first-named snap fastener elements to cooperate therewith, said tapes being adapted to be secured to various garments of a person's wardrobe, and means to releasably connect the ends of the band. 105 110 115

Signed at Los Angeles, California, this 17th day of January, 1923.

NICHOLAS L. BIEHL.
